Primary Examiner — Michelle E. Wilson*Assistant Examiner* — Caitlin A Laverty(74) *Attorney, Agent, or Firm* — Bay State IP, LLC(57) **CLAIM**

The ornamental design for a pill holder as shown and described.

DESCRIPTION

FIG. 1 is a perspective view of a pill holder showing my new design;

FIG. 2 is a top view thereof;

FIG. 3 is a bottom perspective view thereof;

FIG. 4 is a bottom view thereof;

FIG. 5 is a front view thereof; and,

FIG. 6 is a perspective view of the pill holder in an open position.

The left view, right view and rear view of the design are not included as they are identical to the front view shown in FIG. 5.

The broken lines illustrate portions of the pill holder that form no part of the claimed design.
